(57) **CLAIM**

The ornamental design for a steam sterilizer, as shown and described.

DESCRIPTION

FIG. 1 is a front view of a steam sterilizer showing my new design;

FIG. 2 is a rear view thereof;

FIG. 3 is a left view thereof;

FIG. 4 is a right view thereof;

FIG. 5 is a bottom view thereof;

FIG. 6 is a top view thereof; and,

FIG. 7 is a perspective view thereof.

The broken line showing of parts of the drawings is included for the purpose of illustrating use and environment and forms no part of the claimed design.

1 Claim, 7 Drawing Sheets
